UNITED STATES PATENT OFFICE.

JAMES EDDIE MELTON, OF SENATOBIA, MISSISSIPPI.

COAL-GRATE DAMPER.

1,113,032.

Specification of Letters Patent.

Patented Oct. 6, 1914.

Application filed January 8, 1914. Serial No. 811,071.

To all whom it may concern:

Be it known that I, JAMES EDDIE MELTON, a citizen of the United States, residing at Senatobia, in the county of Tate and State 5 of Mississippi, have invented certain new and useful Improvements in Coal-Grate Dampers, of which the following is a specification.

My invention relates to heat regulating devices, particularly to dampers, and has for its object the provision of a novel form of flap damper adapted to be used in connection with coal grates of the type commonly found in dwellings, the damper being so disposed in relation to the grate that its frame rests upon the top of the fire lining just above the arch of the grate frame.

An important object of my invention is to provide a damper of this character which will divide the draft so that the fire will burn evenly from end to end of the grate and also permit of the regulation of the amount of draft, and of the passage of gas to the smoke flue when closed, and which 25 will also prevent an unnecessary consumption of fuel.

Another object is to provide a device of this character which has its weight distributed in such a manner that the material 30 upon both sides of the axis of the pivoted damper will balance regardless of to what extent the damper is opened or closed.

With these and other objects in view, such as simplicity, cheapness, durability and the 35 general improvement of the art, my invention consists in the novel features of construction and arrangement hereinafter described and illustrated in the accompanying drawings, in which:

40 Figure 1 is a vertical sectional view through a grate structure and its flue, showing my device applied thereto, and Fig. 2 is a plan view of the damper removed from the grate.

45 Referring more particularly to the drawings, the numeral 1 designates an ordinary form of grate disposed within the usual casing or fire lining which comprises back and side walls 2 and 3, respectively. As is commonly the practice, the wall 4 of the building is provided with a recess 5 within which the casing is disposed, the back wall 2 thereof being spaced from the wall 4 of the building, as shown. The wall 4 is further provided with a flue 6 communicating with the recess 5, the side and back walls of the cas-

ing or lining terminating at the junction of the recess with the flue. The features just described are common and well known in the art and are shown merely for the purpose of illustrating the adaptation and use of my device.

My improved damper structure is adapted to be placed upon the top edges of the casing or lining and comprises a frame consisting 65 of a main portion 7 and arms 8, the main portion 7 resting upon the back 2 of the casing and the arms 8 resting upon the side walls 3. Adjacent their free ends the arms 8 are provided with grooves 9 for the reception of trunnions 10 formed on the movable damper or plate 11 adjacent the front edge thereof. The plate 11 is held in its normally horizontal position within the supporting frame by means of the engagement 70 of its rear edge 12 with an inwardly projecting flange 13 formed on the main portion 7 of the frame. At a point substantially in a line with the axis of the plate 11, a downwardly extending rigid curved 80 arm 14 is provided which has extending therethrough an aperture 15 which may be engaged by the point of a poker for shifting the angular position of the plate 11.

It is to be noted that the forward portion 85 of the plate 11 is formed heavy and thick, as shown at 16, in order that the weight of the material upon both sides of the axis will balance, thus causing the plate 11 to remain in any angular position to which it may be 90 moved.

Each side of the plate 11 is cut away adjacent the arms 8 of the frame, as shown at 17, to provide openings or spaces 18 through which gas and smoke may escape into the 95 flue 6 when the damper is closed. These openings form an important feature as they cause the draft to be divided and act upon both ends of the fire, thus causing perfect combustion and preventing the waste of fuel. 100 It will be observed that the provision of a smoke and gas exit is therefore assured and that the fire will burn evenly even when the damper is closed. When increased draft is desired it is merely necessary to open the 105 damper by swinging the plate 11 to the desired angle by means of the curved arm 14 formed thereon. It will also be observed that the plate 11 is so constructed and arranged that when it is swung open the opening 110 is at the rear of the casing and the flue, thus causing the draft to pass through the

entire fire before entering the flue through the damper and that this is another feature of my invention which insures perfect combustion of the fuel.

5 Having thus described my invention what I claim is:

A damper comprising a frame, a plate having a relatively thick forward portion, said plate being journaled adjacent its thick portion within said frame, a downwardly projecting curved arm on said plate adjacent said thick portion; the metal in said thick portion of said plate and in said curved arm being so

distributed as to produce equal weight on both sides of the pivotal axis of the plate, 15 and said plate provided at its ends with portions cut-away to distribute the draft and permit of the passage of smoke and gas when the damper is closed.

In testimony whereof I hereto affix my 20 signature in the presence of two witnesses.

JAMES EDDIE MELTON.
